UNITED STATES PATENT OFFICE.

WILLIAM H. CHAPMAN, OF PORTLAND, MAINE, ASSIGNOR TO CHAPMAN ELECTRIC NEUTRALIZER COMPANY, OF PORTLAND, MAINE, A CORPORATION OF MAINE.

PROCESS OF NEUTRALIZING STATIC ELECTRICITY.

No. 844,300.

Specification of Letters Patent.

Patented Feb. 12, 1907.

Application filed February 12, 1906. Serial No. 300,604.

To all whom it may concern:

Be it known that I, WILLIAM H. CHAPMAN, a citizen of the United States of America, and a resident of Portland, Maine, have invented certain new and useful Improvements in Process of Neutralizing Static Electricity, of which the following is a specification.

My present invention relates to a process of removing static electricity from roving or yarn in textile work and from other articles where, as a matter of convenience or necessity, the apparatus must be located at a more or less remote distance from the work. My method consists in placing charged electric conductors at some available point near the material to be treated; but it may be farther away than the charges could of themselves alone have any influence on the material, and then by suitable means creating a current of air which shall pass around or over the conductor and which shall carry the charge across the intervening space, and thus neutralize the static charge in the material subject to the process. For instance, in the process of manufacturing mohair into yarn there is much trouble in the combing-machines and drawing-frames and spinning-frames caused by the material being charged by compression between the rollers, and as the compression is repeated many times in various parts of the machine and as each machine is already crowded with the constituent parts of the machine itself, leaving no available room for additional parts, it becomes important to place the neutralizing apparatus outside of the machine—as, for instance, overhead on the ceiling of the room—and to provide for conveying the neutralizing charges to the material in all parts of the machine at the same time.

A simple means of carrying out my process is shown in the accompanying drawing, in which—

A is a rotary blower, B is a network of electric conductors kept charged through wire *d*, and C is the roving of mohair or other material passing through the rollers *e* of a drawing-frame, whereby it is continually being charged.

The network of the wires B may be kept charged by any suitable means—as, for instance, by a Winshurst machine D or by an

alternator—giving high voltage and having its charges partially or wholly commutated, 55 so as to give the wires a charge which, for the most or the whole of the time, is of a polarity opposite to that of the material under treatment. A proper regulation of the quantity of the air supplied or of the voltage of the 60 electric charge, or both, then enables us to secure perfect neutralization.

I find that in carrying my process into practical use I get good results from an alternating current of unequal pulsations, the long 65 pulsation being of opposite polarity to the charge in the mohair or other body, while the short pulsation is of like polarity. I have used for the purpose an alternation in which the prevailing polarity was three times that of 70 the lesser. By thus producing a charge in which the preponderating kind of electricity is so far in excess of the lesser kind the charge can be conveyed considerable distances by the use of the air-current, and it does not 75 require the accurate regulations which is necessary when the charge is all of one polarity.

In order to carry the charges from the conductor to the article to be neutralized, it is 80 not necessary to have an air-blast of any considerable velocity, as a gentle movement of the air will answer the purpose.

The form of the apparatus here shown may be varied indefinitely, any other suitable devices being used. For instance, the conductor may have a series of points from which the electrical charges may escape into the air, and many forms may be devised for this purpose.

I find that it is important to use a conductor which will admit the air-current passing over and around it, coming into contact with its external surface like the wire-netting above described, since it is a well-known law of 95 electricity that air can only become electrified by coming in contact with the external surface of conductors, the electricity being concentrated at that portion of the conductor.

I claim—

1. The process of neutralizing static electricity in a body consisting of blowing a current of air against said body and placing in said air-current before it reaches said body a 105 conductor charged with electricity of the

opposite polarity to that contained in the body.

2. The process of neutralizing static charges of electricity in a body consisting of 5 blowing a current of air against said body and placing in said air-current a conductor having applied to it an alternating charge of electricity.

3. The process of neutralizing static 10 charges of electricity in a body consisting of

blowing a current of air against said body and placing in said air-current a conductor having an alternating charge of electricity with a series of relatively long and short impulses of which the long impulses have a polarity opposite to that of the charged body. 15
